UNITED STATES PATENT OFFICE

2,104,914

CIRCUIT BREAKER

Robert Temple, Jr., Brooklyn, N. Y.

Original application April 24, 1933, Serial No. 667,686, now Patent No. 2,017,329, dated October 15, 1935. Divided and this application October 14, 1935, Serial No. 44,903

12 Claims. (Cl. 200—150)

This invention relates to circuit breakers and constitutes a division of my copending application on explosively actuated devices, Ser. No. 667,686, filed April 24, 1933 now Patent No. 2,017,329, issued October 15, 1935.

The invention is more particularly directed to an oil circuit breaker, employing an explosive charge to actuate the same. The present circuit breaker is adapted both for high and low current circuits and is so constructed that the circuit may be opened either when an overload occurs, or at any other desired time, without producing an arc.

A large number of oil and other circuit opening devices have been produced, but these for the most part are rather complicated and exceedingly expensive devices. The present invention may or may not be immersed within an oil bath and the device is constructed in such a manner as to open the circuit in a way that no appreciable or continued arc can occur between the contact points.

Another object of the invention is the provision of an explosively actuated circuit breaker, the operation of which is so positive that the circuit will be broken even though the overload has been so great as to fuse the contact points together.

In the drawings, Fig. 1 is a broken top plan view of the preferred embodiment of the invention, the view being largely in section;

Fig. 2 is a broken side elevation thereof;

Fig. 3 is a broken top plan view, largely in section, of a modified form of the invention; and

Fig. 4 is a broken side elevation thereof.

The preferred embodiment of the invention illustrated in Figs. 1 and 2 is mounted on a base 10 and includes a pair of stationary contact members 11 and 12, which are mounted in spaced relation to the base by means of supporting members 13 and 14. Each stationary contact member is formed with a longitudinal aperture 15 extending inwardly from its outer end, the outer end of said apertures being outwardly flared, as indicated at 16. In order to make a more firm contact between the stationary and the moveable contact members, the apertures are provided with a plurality of annular recesses 17 in which compression rings 18 are fitted.

The moveable contact member 20 is substantially U-shaped and is formed with a longitudinal aperture 21 extending from end to end. The terminals of the moveable contact member are tapered, as shown at 22, in order to facilitate their admission into the aperture. The moveable contact member is carried by a hollow plunger 24, having a longitudinal aperture 25 which communicates with the aperture 21, the plunger also

being provided with flanges 19 to insure a more firm engagement with the member 20. The plunger 24 is slidably mounted within a barrel 26 having a longitudinal aperture 27, the barrel being positioned in spaced relation to the base by means of a supporting member 28, said supporting member having an upper clamping portion 28'. When the circuit breaker is in a closed position, as illustrated in Fig. 1, the inner end of the plunger 24 abuts against a shoulder 29 in the barrel.

Adjacent to the shoulder 29, the aperture in the barrel is formed with a reduced portion 31 within which the forward end of a second plunger 32 is positioned when the circuit breaker is in a closed position. An oil port or inlet 33 is formed in the barrel at a point adjacent to the forward end of the plunger 32 when the circuit breaker is in a closed position. The oil inlet leads to an oil reservoir 34 and so long as the plunger 32 is in the position shown in Fig. 1, the chambers within the plunger 24 and the moveable contact members are completely filled with oil. At the rear end of the plunger a hollow piston 35 is permanently secured, the piston closely fitting an enlarged portion 36 of the aperture in the barrel. In order to insure a close fit between the piston and the barrel, said piston is provided with a plurality of spaced piston rings 38. When the detonation takes place, as hereinafter described, the piston and the plunger 32 move forward, and, in order to return the piston thereafter to its normal position, a coil compression spring 39 is positioned between the forward end of the piston and a shoulder 40. Inasmuch as the area within the aperture 36 is closed, the forward moving piston 35 compresses the air therein which forms a cushion to prevent the piston from striking the shoulder 40 too severely. In order to reduce the compression, however, air outlet ports 41 are formed in the portion of the barrel adjacent to the shoulder 40.

The rear end of the barrel is provided with an enlarged breech portion 42 and is supported in spaced relation to the base by means of a bracket 43 having a clamping portion 44. The rear end of the aperture 36 in the barrel is threaded, as at 45, to receive a breeching element 46 having a longitudinal aperture 47 to receive a blank cartridge 48.

When an overload in the circuit occurs, the cartridge is detonated in the following manner. A breech block 49 having a reduced threaded forward portion 50, is fitted within a threaded aperture at the rear end of the breeching element.

A firing pin 52 is mounted within a longitudinal aperture 53 in the breech block. Thus, when it is desired to actuate the circuit breaker, the firing pin is caused to strike the cartridge by a suitable mechanical or electrical means. This causes the explosive gases to act upon the piston, thereby driving the plunger 32 forward, the initial movement thereof closing the oil port. Further movement of the piston 32 places the oil under an exceedingly high pressure which reacts against the inner ends 55 and 56 of the apertures 15 in the stationary contact members, thereby causing the moveable contact member to travel in the direction of movement of the plunger 32. Movement, of course, proceeds after the oil begins to escape and as this movement continues at an exceedingly high velocity, and the oil, which is under a continuously increasing pressure, is forcibly moved outwardly in the annular area between the stationary and moveable contact members. The oil is under a sufficiently high pressure and velocity to prevent the formation of a vacuum and any appreciable or continued arc as well.

In order to limit the outward movement of the moveable contact member, the plunger 24 is provided at its forward end with an integrally formed solid rod 58, having a reduced portion 59 at its forward end. The rod passes through a closed cylinder 60, the cylinder having two or more opposed ports 61 adjacent to its forward end, the cylinder being suitably supported on a port 62. The reduced portion of the rod carries a piston 63 which compresses the air within the cylinder after said piston has passed the ports 61, thereby forming an air cushion at the forward end of the cylinder. In some instances, it may be desirable to place a resilient gasket 64 at the forward end.

When the circuit breaker is actuated, the moveable contact member has moved forward to the position shown in the broken lines in Fig. 1. It may then be returned to its closed position by manipulation of the lever 65, which is pivotally mounted on the base at 66.

The modified embodiment of the invention shown in Figs. 3 and 4, is similar to the preferred embodiment of the invention except that it is provided with only a single moveable contact member rather than a double one, as in the preferred embodiment. In this instance, the barrel 70 is mounted in spaced relation to the base 71 by means of a supporting element 72 which is secured to the base and is provided with a clamping portion 72'. The barrel is formed with a longitudinal aperture 73 having an outwardly flared portion 74 at its forward end. Substantially midway between the ends of the barrel an oil inlet port 75 is positioned, this inlet leading to the oil reservoir 76. Adjacent to the oil port, the barrel is formed with an enlarged portion 78 and the aperture 79 in this portion is correspondingly enlarged.

The plunger 80 is similar to that shown in the preferred embodiment and likewise carries a hollow piston 82 at its rear end, the piston having a plurality of piston rings 83. This portion of the barrel is also supported in spaced relation to the base on a supporting element 84 having an upper clamp 85. The breeching element 87 is screw threaded into an enlarged portion 88 in the rear end of the barrel, this breeching element having a longitudinal aperture 89 in which the cartridge 90 is positioned. The breech block 91 and firing pin 92 are similar to that shown in the preferred embodiment.

The rear end of the moveable contact member

94 is provided with a plurality of spaced contact rings 95 and normally resides at a point substantially half-way within the aperture 73 in the barrel, this plunger being supported for longitudinal movement in a supporting member 96 having an aperture 97 therein. The moveable contact member is further provided with a second set of contact rings 98, which are adjacent to the aperture 97 when the circuit breaker is in a closed position. The closed cylinder 100, the reduced portion 101 of the moveable contact member, the piston 102, and the buffer 103, are similar to that shown in the preferred embodiment. Likewise, the circuit breaker is adapted to be reset by actuating the lever 104 which is pivotally mounted to the base at 105. The screw 106 may serve as the terminal for the fixed contact and the screw 107 for the moveable one.

Although not shown in the drawings, each of the embodiments of the present invention may, if desired, be immersed in oil. This is not essential for the successful operation of the device, however, since the oil is forced outwardly between the fixed and moveable contact members at such a velocity and pressure as to quench any arc that may be formed.

What I claim is:—

1. A circuit breaker comprising stationary and moveable contact members, the latter having a fluid filled chamber, a piston free for movement independent of the moveable contact member adapted to compress the fluid and thereby actuate the moveable contact member and explosively actuated means for moving the piston.

2. In a circuit breaker, the combination of a fixed contact member and a moveable contact member having a fluid filled chamber therein, communicating with the fixed contact member, a plunger free for movement independent of the moveable contact member adapted to compress the fluid and thereby actuate the moveable contact member and explosively actuated means for moving the plunger.

3. In an explosively actuated circuit breaker, a pair of apertured stationary contact members, a U shaped hollow moveable contact member, the ends of which pass into the stationary contact members, a hollow plunger carrying said U shaped contact member, a fluid carried within said hollow member, an explosively actuated piston associated within said hollow plunger, whereby, when the piston is actuated, the moveable contact member will pass from the stationary contact members and the fluid will be expelled under pressure.

4. A circuit breaker comprising a hollow cylindrical contact member, a funnel-shaped guide integral with one end of the cylindrical contact member, a second contact member normally positioned in the first-named member and in electrical contact therewith, means defining a chamber in communication with the hollow cylindrical portion of the first contact member, electrical insulating liquid in the chamber, a piston movable into engagement with the fluid in the chamber, explosive means for moving the piston, pneumatic and metal spring means for damping the movement of the piston, and pneumatic means for damping the movement of the contact members apart as a result of the movement of the piston, said insulating fluid being forced rapidly between the contact members by the piston as the members are moved apart.

5. A circuit breaker comprising a hollow cylindrical contact member, a second contact member

- normally positioned in the first-named member and in electrical contact therewith, means defining a chamber in communication with the hollow cylindrical portion of the first contact member, 5 electrical insulating liquid in the chamber, a piston movable into engagement with the fluid in the chamber, explosive means for moving the piston, means for damping the movement of the piston, and means for damping the movement of the 10 contact members apart as a result of the movement of the piston, said insulating fluid being forced rapidly between the contact members by the piston as the members are moved apart.
6. A circuit breaker comprising a hollow cylindrical contact member, a second contact member normally positioned in the first-named member and in electrical contact therewith, means defining a chamber in communication with the hollow cylindrical portion of the first contact member, 15 electrical insulating liquid in the chamber, a piston movable into engagement with the fluid in the chamber, and explosive means for moving the piston, said insulating fluid being forced rapidly between the contact members by the piston as the members are moved apart.
7. A circuit breaker comprising a hollow cylindrical contact member, a second contact member normally positioned in the first-named member and in electrical contact therewith, means defining a chamber in communication with the hollow cylindrical portion of the first contact member, 20 electrical insulating liquid in the chamber, a piston movable into engagement with the fluid in the chamber, explosive means for moving the piston, means for damping the movement of the piston, and means for damping the movement of the contact members apart as a result of the movement of the piston.
8. A circuit breaker comprising in combination, 25 a pair of engaging electrical contacts, means mounting the contacts for relative movement, and explosive means for moving the contacts apart and simultaneously forcing insulating liquid in considerable quantities and at explosive pressures between the contacts.
9. A circuit breaker comprising in combination, 30 a pair of engaging electrical contacts, means mounting the contacts for relative movement, means for moving the contacts apart and simultaneously forcing insulating liquid in considerable quantities and at relatively high pressures between the contacts, means for damping movement of the contact-moving means, and means for damping relative movement of the contacts.
10. In combination, a cup-shaped member, a 35 hollow rod slidably received in fluid-tight relation in the member, fluid carried in the hollow rod, a piston movable into compressing relation with the fluid to thereby forcibly eject the rod from the cup, and explosive means for moving the piston.
11. In combination, a pair of spaced contacts, 40 means bridging and electrically connecting the contacts, and fluid-pressure means adapted on electrical overload to apply fluid-pressure forces through an insulating liquid directly between each contact and the portion of the bridging means engaging therewith to positively move the bridging means away from each contact while rapidly discharging the liquid between each contact and its associated portion of the bridging means.
12. In combination, a pair of spaced contacts, 45 means bridging and electrically connecting the contacts, and fluid-pressure means adapted on electrical overload to apply fluid-pressure forces through an insulating liquid directly between each contact and the portion of the bridging means engaging therewith to positively move the bridging means away from each contact.

ROBERT TEMPLE, JR.
